DESIGN FOR A CHILD'S COMBINED DESK AND TOY CHEST, OR THE LIKE

Paul Metro, Brookfield, Ohio

Application May 21, 1947, Serial No. 139,189

Term of patent 7 years

(Cl. D15—8)

To all whom it may concern:

Be it known that I, Paul Metro, a citizen of the United States, residing at Brookfield, in the county of Trumbull and the State of Ohio, have invented a new, original, and ornamental Design for Child's Combined Desk and Toy Chest, or the like, of which the following is a specification, reference being had to the accompanying drawing, forming a part thereof.

In the drawing:

Figure 1 is a perspective view of the combined desk and toy chest, showing my new design, and Figure 2 is a transverse sectional view of the same.

I claim:

The ornamental design for a child's combined desk and toy chest, or the like, substantially as shown.

PAUL METRO.
